ABSTRACT: The present invention is concerned with com-
pounds of formula

wherein R₁ is heteroaryl and R₂ is alkyl, aryl, or heteroaryl.
Compounds of this invention exhibit central nervous system
depressant properties.

N-PYRIDINE 5-AMINO OXAZOLES

The present invention relates to N-heteroaryl 5-amino-oxazoles having the following structural formula:

wherein R₁ is heteroaryl and R₂ is lower alkyl, aryl, aralkyl, or heteroaryl.

In the above definitions for R₁ and R₂, the term "heteroaryl" encompasses the monocyclic and bicyclic hetero aromatic compounds having at least one hetero atom in the ring which may be either nitrogen, oxygen or sulfur. Representative heteroaryl radicals falling within this definition are, for example, pyridine, quinoline, pyrrole, indole, thiophene, benzimidazole, tetrazole, pyrimidine and the like. The term "aryl" denotes an aromatic radical, preferably of six to 10 carbon atoms, such as for example, phenyl, tolyl and the like. The term "aralkyl" encompasses lower alkyl groups in which an aryl group as defined above is substituted for a hydrogen atom, such as for example, benzyl, phenethyl and the like. The term "lower alkyl" as used herein includes lower aliphatic hydrocarbons having one to five carbon atoms arranged in a straight carbon chain.

The compounds of this invention are useful in cases where a reduction in skeletal muscle spasm is indicated. For example, at a dose of 200 mg./kg. intraperitoneally in laboratory animals, such as rats, the compounds of this invention produce a reduction in body tone lasting for 24 hours. Simultaneously, the motor activity and temperature are also decreased for a period of about 3 to 6 hours. Generally speaking, a dose range from 100 to 500 mg./kg. is recommended to produce the desired reduction in motor activity. This dosage regimen may, of course, be varied according to body weight, sex, age, species of the mammal being treated as well as the severity of the condition being treated, by methods well known to the healing art.

In order to use these compounds, they are formulated with such standard pharmaceutical carriers, such as lactose, mannitol, dicalcium phosphate into dosage forms such as tablets, capsules, and the like. They can also be combined with parenterally acceptable vehicles such as sesame oil, arachis oil and the like to form dosage forms suitable for parenteral injection.

According to the present invention, compounds of type I are prepared by acylation of heteroaryl amines of type III with azlactones of type II followed by cyclodehydration of the intermediate compounds of type IV. The foregoing reaction is illustrated by the following schematic diagram:

in which R₁ and R₂ are as previously defined.

Starting compounds III are readily available from commercial sources, for example, Aldrich Chemical Co. Azlactones of type II were prepared by the procedure described in Organic Syntheses, Vol. 47, p. 101 (John Wiley & Sons, Inc., New York, N.Y., 1967).

The following examples are included in order further to illustrate the invention.

EXAMPLE 1

N-[(Indol-2-ylcarbamoyl)methyl]benzamide

To a solution of 1.6 g. of 2-phenyl-5-oxazole in 100 ml. of THF is added 1.7 g. of 2-aminoindole ·HCl and 0.9 g. of sodium acetate and the mixture is refluxed for 2 hrs. The solvent is removed under reduced pressure and the residue is recrystallized from 95% EtOH. M.P. 211-212°; yield: 2.5 g. (85%). Anal. Calcd. for C₁₇H₁₅N₃O₂: C, 69.61; H, 5.15; N, 14.33. Found: C, 69.53; H, 5.39; N, 14.53.

EXAMPLE 2

N-[(2-Pyridylcarbamoyl)methyl]benzamide

A solution of 1 g. 2-aminopyridine and 1.75 g. of 2-phenyl-5-oxazolone in 50 ml. of THF is refluxed for 9 hrs. Concentration to half the original volume and chilling on an ice bath produces crystals, which are recrystallized from ethyl acetate. M.P. 172°-174°; Yield: 0.6 g. (21%).

Anal. Calcd. for C₁₄H₁₃N₃O₂: C, 65.87; H, 5.13; N, 16.46. Found: C, 65.85; H, 5.07; N, 16.65.

EXAMPLE 3

N-[(1H-Tetrazol-5-ylcarbamoyl)methyl]benzamide

A solution of 1 g. 5-amino-1H-tetrazole, 1.6 g. 2-phenyl-5-oxazolone in 100 ml. THF is refluxed for 5 hrs. Crystals which separate out of the hot solution are filtered off, slurried twice, at 1 hour each, with THF, filtered and dried. M.P. 254°-256°; yield: 2.3 g. (90%).

Anal. Calcd. for C₁₆H₁₀N₅O₂: C, 48.78; H, 41.09; N, 34.14. Found: C, 48.56; H, 4.15; N, 34.17.

EXAMPLE 4

N-[(2-Benzothiazolylcarbamoyl)methyl]benzamide

A solution of 1 g. 2-aminobenzothiazole, 1.08 g. of 2-phenyl-5-oxazolone and 50 ml. THF is refluxed for 7½ hrs. The precipitate is filtered off and recrystallized from 95% EtOH (≈450 ml./gm.). M.P. 262°-264°; yield: 1.4 g. (70%).

Anal. Calcd. for $C_{18}H_{13}N_3O_2S$: C, 61.72; H, 4.21; N, 13.50; S, 10.30. Found: C, 61.75; H, 4.31; N, 13.48; S, 10.43.

EXAMPLE 5

N-[(2-Benzimidazolylcarbamoyl)methyl]benzamide

A solution of 0.5 g. 2-aminobenzimidazol and 0.6 g. of 2-phenyl-5-oxazolone in 50 ml. of THF is refluxed until a product separates out ($\approx$ 30 min.). This is filtered off and recrystallized from 95% EtOH. M.P. 303°-305°; yield: 0.9 g. (82%).

Anal. Calcd. for $C_{18}H_{14}N_3O_2$: C, 65.29; H, 4.80; N, 19.04. Found: C, 65.2; H, 4.92; N, 18.99.

EXAMPLE 6

N-[(2-Quinolylcarbamoyl)methyl]benzamide

Is prepared in the same manner as N-[(2-pyridyl carbamoyl)methyl]benzamide using 1 g. 2-aminoquinoline, 1.1 g. 2-phenyl-5-oxazolone and THF. The product is recrystallized from absolute EtOH. M.P. 218°-219°; yield: 1.7 g. (81%).

Anal. Calcd. for $C_{18}H_{13}N_3O_2$: C, 70.80; H, 4.95; N, 13.76. Found: C, 70.98; H, 5.00; N, 13.95.

EXAMPLE 7

N-[N-Methylphenylcarbamoyl]methyl]benzamide

Is prepared in same manner as N-[(2-pyridyl carbamoyl)methyl]benzamide using 3 g. N-methylaniline, 4.5 g. 2-phenyl-5-oxazolone in 50 ml. THF and refluxing for 28 hrs. The product is recrystallized from Skelly B. M.P. 84°-85°; yield: 4.7 g. (63%).

Anal. Calcd. for $C_{18}H_{16}N_3O_2$: C, 71.62; H, 6.01; N, 10.44. Found: C, 71.70; H, 6.02; N, 10.18.

EXAMPLE 8

N-[(1-Methylindol-2-yl)carbamoyl]methyl]benzamide

Is prepared in the same manner as N-[(2-indolyl carbamoyl)methyl]benzamide, using 1.1 g. 1-methyl-2-amino in-dole HCl 1 g. 2-phenyl-5-oxazolone, 0.5 g. sodium acetate in

50 ml. THF and refluxing for 6 hrs. The product is recrystallized from abs. EtOH. M.P. 202°-204°; yield: 1.1 g. (59.5%).

Anal. Calcd. for $C_{18}H_{17}N_3O_2$: C, 70.34; H, 5.58; N, 13.67. Found: C, 70.14; H, 5.78; N, 13.51.

5

EXAMPLE 9

N-[(5-Chloropyrid-2-yl)carbamoyl]methyl]benzamide

Is prepared in the same manner as N-[(2-pyridyl carbamoyl)methyl]benzamide using 1 g. 2-amino-5-chloropyridine, 1.25 g. 2-phenyl-5-oxazolone, in 50 ml. THF and refluxing for 18 hrs. The product is recrystallized from abs. ethanol. M.P. 229°-230°; yield: 1.6 g. (71.5%).

Anal. Calcd. for $C_{14}H_{12}N_3O_2Cl$: C, 58.04; H, 4.18; N, 14.50. Found: C, 57.77; H, 4.16; N, 14.25.

25

EXAMPLE 10

N-[(3-Pyridylcarbamoyl)methyl]benzamide

Is prepared in the same manner as N-[(2-pyridyl carbamoyl)methyl]benzamide using 2 g. of 3-aminopyridine, 3.5 g. of 2-phenyl-5-oxazolone and 50 ml. of THF. The product is recrystallized from acetonitrile. M.P. 193°-195°; yield: 2.3 g. (43%).

Anal. Calcd. for $C_{14}H_{13}N_3O_2$: C, 65.87; H, 5.13; N, 16.46. Found: C, 66.16; H, 5.22; N, 16.50.

50

EXAMPLE 11

N-[(2-Pyrimidinylcarbamoyl)methyl]benzamide

Is prepared in the same manner as N-[(2-pyridyl carbamoyl)methyl]benzamide using 2 g. of 2-aminopyrimidine, 3.4 g. 2-phenyl-5-oxazolone and 50 ml. THF. The product is recrystallized from ethyl acetate. M.P. 219°-220°; yield: 0.3 g. (55%).

Anal. Calcd. for $C_{13}H_{12}N_3O_2$: C, 60.93; H, 4.72; N, 21.87. Found: C, 60.78; H, 4.74; N, 21.87.

65

EXAMPLE 12

N-[(2-Thiazolylcarbamoyl)methyl]benzamide

Is prepared in the same manner as N-[(2-pyridyl carbamoyl)methyl]benzamide using 1 g. of 2-aminothiazole, 1.6 g. of 2-phenyl-5-oxazolone and 50 ml. THF refluxing for 4 hrs.

70

The product is recrystallized from abs. EtOH. M.P. 238°-239°; yield: 1.3 g. (50.5%).

Anal. Calcd. for $C_{12}H_{11}N_3O_2S$: C, 55.16; H, 4.24; N, 16.08; S, 12.27. Found: C, 55.32; H, 4.40; N, 16.29; S, 12.21.

EXAMPLE 13

2-[(2-phenyl-5-oxazolyl)amino]pyridine

5 g. N-[(2-pyridyl carbamoyl)methyl]benzamide is added to 100 g. of PPE and stirred for 45 hrs. The solution is poured onto 300 ml. of ice and water with stirring and basified with ammonium hydroxide. The precipitate is filtered, washed with water and is recrystallized from abs. ethanol. M.P. 169°-170°; yield: 1.5 g. (32%).

Anal. Calcd. for $C_{14}H_{11}N_3O$: C, 70.87; H, 4.67; N, 17.71. Found: C, 70.98; H, 4.71; N, 17.80.

EXAMPLE 14

2-[(2-phenyl-5-oxazolyl)amino]benzimidazole

Is prepared in the same manner as 2-[(phenyl-5-oxazolyl)amino]pyridine using 10 g. N-[(2-benzimidazolylcarbamoyl)methyl]benzamide, and 200 gm. PPE. The product is recrystallized from 95% ethanol. M.P. 238°-239°; yield: 7.1 g. (70%).

Anal. Calcd. for $C_{16}H_{12}N_3O$: C, 69.55; H, 4.38; N, 20.28. Found: C, 69.61; H, 4.39; N, 20.57.

EXAMPLE 15

2-[(2-phenyl-5-oxazolyl)amino]benzothiazole

Is prepared in the same manner as 2-[(phenyl-5-oxazolyl)amino]pyridine using 5 g. N-[(2-benzothiazolylcarbamoyl)methyl]benzamide and 100 g. of PPE. The product is recrystallized from abs. ethanol. M.P. 228°-229°; yield: 3 g. (60%).

Anal. Calcd. for $C_{16}H_{11}N_3OS$: C, 65.51; H, 3.78; N, 14.32; S, 10.93. Found: C, 65.55; H, 3.89; N, 14.31; S, 11.16.

EXAMPLE 16

2-[(2-phenyl-5-oxazolyl)amino]thiazole

20 Is prepared in the same manner as 2-[(phenyl-5-oxazolyl)amino]pyridine using 6 g. N-[(2-thiazolylcarbamoyl)methyl]benzamide and 150 g. PPE. The product is recrystallized from abs. ethanol. M.P. 190°-191°; yield: 3.8 g. (63.5%).

25 Anal. Calcd. for $C_{12}H_{11}N_3OS$: C, 59.24; H, 3.73; N, 17.27. Found: C, 58.95; H, 4.02; N, 17.12; S, 13.07.

EXAMPLE 17

5-Chloro-2-[(2-phenyl-5-oxazolyl)amino]pyridine

45 Is prepared in the same manner as 2-[(phenyl-5-oxazolyl)amino]pyridine using 2 g. of N-[(5-chloropyrid-2-yl carbamoyl)methyl]benzamide and 4.5 g. PPE. The product is recrystallized from 95% ethanol. M.P. 231°-232°; yield: 1.2 g. (62%).

50 Anal. Calcd. for $C_{14}H_{10}N_3OCl$: C, 61.89; H, 3.71; N, 15.47; Cl, 13.05. Found: C, 62.01; H, 3.72; N, 15.35; Cl, 13.05.

EXAMPLE 18

2-[(2-phenyl-5-oxazolyl)amino]quinoline

70 Is prepared in the same manner as 2-[(phenyl-5-oxazolyl)amino]pyridine using 3.7 g. of N-[(2-quininolyl carbamoyl)methyl]benzamide and 75 g. of PPE. The product is recrystallized from ethyl acetate. M.P. 190°-192°; yield: 2.7 g. (72%).

Anal. Calcd. for $C_{18}H_{13}N_3O$: C, 75.24; H, 4.56; N, 14.63. 75 Found: C, 75.15; H, 4.56; N, 14.60.

EXAMPLE 19

3-[(2-phenyl-5-oxazolyl)amino]pyridine

Is prepared in the same manner as 2-[(phenyl-5-oxazolyl)amino]pyridine using 1 g. of N-[(3-pyridyl carbamoyl)methyl]benzamide, 25 g. PPE and stirring for 72 hrs. The product is recrystallized from toluene. M.P. 148°-150°; yield: 0.5 g. (49%).

Anal. Calcd. for $C_{14}H_{11}N_3O$: C, 70.87; H, 4.67; N, 17.71. Found: C, 70.89; H, 4.76; N, 17.57.

EXAMPLE 20

2-[(2-Phenyl-5-oxazolyl)amino]indole

4.5 g. of N-[(indol-2-yl carbamoyl)methyl]benzamide is stirred with 90 g. PPE for 45 hrs. The solution is poured onto ≈300 ml. of ice and water with stirring and basified with ammonium hydroxide. The precipitate is filtered off and washed well with water. Yield: 3.8 g. (94%). The product is recrystallized from acetonitrile. M.P. 238°-240°; yield: 1.6 g. (39.5%).

Anal. Calcd. for $C_{17}H_{13}N_3O$: C, 74.16; H, 4.73; N, 15.26.

15

1-Methyl-2-[(phenyl-5-oxazolyl)amino]indole

Is prepared in the same manner as 2-[(phenyl-5-oxazolyl)amino]pyridine using 1.4 g. of N-[(1methyl indol-2-yl)carbamoyl]methyl benzamide and 35 g. PPE. The product is recrystallized from abs. ethanol. M.P. 205°-206°; yield: 0.8 g. (60%).

Anal. Calcd. for $C_{18}H_{15}N_3O$: C, 74.72; H, 5.23; N, 14.53. Found: C, 74.47; H, 5.27; N, 14.36.

I claim:

1. A compound of the formula:

wherein R_1 is pyridine or chloropyridine and R_2 is lower alkyl or phenyl.

2. A compound according to claim 1 which is 2-[(phenyl-5-oxazolyl)amino]pyridine.

3. A compound according to claim 1 which is 5-chloro-2-[(2-phenyl-5-oxazolyl)amino]pyridine.

4. A compound according to claim 1 which is 3-[(2-phenyl-5-oxazolyl)amino]pyridine.
